UNITED STATES PATENT OFFICE

136,984

DESIGN FOR A COMBINATION WALKER AND STROLLER OR SIMILAR ARTICLE

John E. Richardson, Pico, Calif.

Application February 6, 1943, Serial No. 109,471

Term of patent 7 years

To all whom it may concern:

Be it known that I, John E. Richardson, a citizen of the United States, residing in Pico, in the county of Los Angeles, State of California, have invented a new, original, and ornamental Design for a Combination Walker and Stroller or Similar Article, of which the following is a specification, reference being had to the accompanying drawings, forming a part thereof.

nation walker and stroller embodying my novel design.

I claim:

The ornamental design for a combination walker and stroller or similar article, as shown.

JOHN E. RICHARDSON.
